UNITED STATES PATENT OFFICE.

ALMON E. NORRIS, OF CAMBRIDGE, MASSACHUSETTS.

HOISTING AND CONVEYING APPARATUS.

No. 922,807.

Specification of Letters Patent.

Patented May 25, 1909.

Original application filed January 14, 1905, Serial No. 241,072. Divided and this application filed June 8, 1906.
Serial No. 320,731.

To all whom it may concern:

Be it known that I, ALMON E. NORRIS, a citizen of the United States, residing at Cambridge, in the county of Middlesex and 5 State of Massachusetts, have invented an Improvement in Hoisting and Conveying Apparatus, of which the following description, in connection with the accompanying drawings, is a specification, like letters on the 10 drawings representing like parts.

My invention consists in improvements in hoisting and conveying apparatus and particularly in improvements relating to hoisting and conveying systems employing a cable 15 or other track-way along which there is adapted to travel a trolley carriage carrying suitable load-hoisting devices.

It also consists in improvements in rope guiding and equalizing devices, and in the 20 construction of the trolley carriage itself.

This application is a division of my prior co-pending application Ser. No. 241,072, filed January 14, 1905.

My invention will be best understood by 25 reference to the following description, when taken in connection with the accompanying drawings, of one specific embodiment thereof, while its scope will be more particularly pointed out in the appended claims.

30 In the drawings,—Figure 1 is a plan in outline of a hoisting engine provided with winding drums illustrating one form or embodiment of my invention; Fig. 2 is a side elevation of the same; Fig. 3 is an enlarged 35 view, partially broken away and partially in section, of the winding drums and driving connections shown in Fig. 1; Figs. 4 and 5 are diagrammatic views showing the cable connections which may be employed, and 40 the cable movements during hoisting and traversing respectively; Figs. 6 and 7 show an improved form of trolley carriage in plan and side elevation respectively; Fig. 8 shows, 45 partially broken away, the details of one form of rope-equalizing device looking from underneath the carriage seen in Fig. 6, and Fig. 9 is an end elevation of the same, also broken away.

In the drawings I have shown, for illustrative purposes, a hoisting engine mounted 50 upon the bed plate *a* provided with the two cylinders *b* and *b'*, having piston rods, one of which, *c*, is shown in Fig. 2, connecting rods *d* and *d'* and crank disks *e* and *e'*, the latter 55 connected directly to the drum shaft *f* (see

Fig. 3). While this double cylinder, steam hoisting engine is selected to illustrate my invention, it is to be understood that the latter is not limited to any particular type or form of motive means. The drum shaft 60 is suitably journaled in bearings *e* carried by the engine frame *a* and has upon it the two winding drums *g* and *h*, which may be of any suitable construction, but which herein I have shown each of a shape adapted to be 65 embraced by several convolutions of an endless cable to provide the necessary friction for transmitting power to the trolley carriage through the cable as one strand thereof winds upon the drum and the other unwinds. 70

The winding drums shown herein are intended to be operated at will in one direction at one speed, and at a reduced speed in a reversed relation, and the means for attaining this end will be best understood by reference 75 to Fig. 3. The drum *f* has fixedly secured to it, to rotate therewith, the pinion *g'*, the teeth of which mesh with one or more pinions *g*², the latter journaled upon studs *g*³ secured to and carried by the part *g*⁴, to which the drum 80 *g* is rigidly attached. Meshing also with the pinion *g*² is an internal gear *g*⁵ carried by or formed upon the member *g*⁶, which latter is mounted for free rotation upon the drum shaft *f*. Near the opposite end of the hoisting 85 apparatus and upon the drum shaft is provided a second pinion *h'* keyed or otherwise secured to the drum shaft and meshing with one or more intermediate pinions *h*² journaled upon the studs *h*³, the latter being, however, secured to and carried by the member 90 *h*⁴, which, like the member *g*⁶, is journaled for free rotation upon the drum shaft. The pinion *h*² also gears with the internal gear *h*⁵ which is formed upon or carried by the part 95 *h*⁶ fixedly attached to the winding drum *h*. The free rotatable members *g*⁶ and *h*⁴ have formed upon their peripheries suitable brake surfaces embraced by the brake bands *g*⁷ and *h*⁷ respectively, which are so connected 100 to the rocker shaft *i* (Fig. 1) that a movement of the hand lever *i'* (Fig. 2) connected to the rocker shaft *i* through links *i*² and *i*³, will serve to securely and simultaneously clasp the said bands *g*⁷ and *h*⁷ about the surfaces of their 105 respective brake drums to oppose and completely stop further movement thereof. When this takes place, rotation of the drum shaft drives the pinion *h'* in one direction, the pinion *h*², the axis of which is now stationary, 110

in the opposite direction, and the gear h^5 and the drum h also in an opposite direction and at a suitably reduced speed. The pinion g' rotating in the same direction as the pinion h' causes the pinion g^2 to move and travel about the internal gear g^5 , now held fast, so that the drum g is caused to rotate in the same direction as the pinion g' and oppositely to the drum h . The relative sizes of 10 the different gears is preferably such that while the two drums g and h rotate in opposite directions, as has been seen, and at a speed relatively less than that of the shaft f , the speed of the two winding drums is substantially the same.

Referring now to Figs. 4 and 5, I have there indicated diagrammatically the relation of the operating cables to the winding drums g and h and the trolley carriage. The 20 latter designated by k , is adapted to run upon the cable-way l . In the simplest and preferred embodiment of my invention the carriage is provided with two winding drums k' secured each to one end of the depending 25 hoisting rope k^2 carrying the skip hook k^3 and adapted when oppositely rotated to raise or lower the said hook. Secured to the hoisting drums k' are the larger winches k^4 , about which are carried with several turns 30 the opposing loops l' and l^2 of the operating cable system which herein, and preferably, comprises a single endless cable. The strand l^3 of the loop l' passes to the end of the cable-way at which the drums g and h are 35 located, to and about the drum h and returning forms the strand l^4 , which passes to the opposite end of the cable-way and thence about suitable sheaves again to the trolley carriage to form one strand of the loop l^2 . 40 The other strand l^5 of the loop l' passes to and about the drum g and thence forming the strand l^6 passes to the opposite end of the cable-way and thence to the carriage to form the remaining strand of the loop l^2 . 45 When the brake bands g^7 and h^7 are tightened to throw in the slow reverse speed, the drums g and h rotate in the relations shown in Fig. 4 and cause the respective strands of the endless cable to move in the directions indicated 50 by the arrows, from which it will be seen that the winches k^4 are caused to be oppositely rotated to raise the hook k^3 and effect hoisting of the load. During this operation no change in position of the carriage is effected, 55 for the loops l' and l^2 remain of the same length, one strand of each being paid out as rapidly as the other is drawn in. When the load has been hoisted and it is desired to cause travel of the carriage, the latter may 60 be effected by producing conditions of cable movement shown in Fig. 5, where it will be observed that the direction of movement of the drum h has been reversed, the new relative rotation of the drums preferably taking 65 place, as it will appear, at an increased speed.

As will be seen from the arrows indicating the direction of cable movement, this causes a similar movement of each strand of the two opposing loops, so that one loop is lengthened while the other is correspondingly shortened with the result that, without movement of the winches k^4 or hoisting drums k' , the carriage has traversed in the direction of the lengthened loop. Thus, in Fig. 5, the loop l' 70 will continue to be lengthened and the loop l^2 shortened so long as the rotation of the drums g and h is carried on and the trolley carriage k will be moved to the left, the hook and its attached load however being held in its initial elevated position.

Referring now to Fig. 3 and also to Figs. 1 and 2, the reverse movement of the winding drums is preferably effected by causing them to be driven directly from the driving shaft f . In the form of my invention shown in Fig. 3, a clutch member m is fixedly secured to the shaft f intermediate the rotatable members g^6 and h^4 . The latter are provided with cone-shaped surfaces g^8 and h^8 , respectively, which overlie and coöperate with corresponding surfaces upon the clutch member m , in connection with suitable friction material m' intermediate the two sets of surfaces, forming thereby a clutch device for clutching the rotatable members to the 90 shaft. The two clutches are thrown simultaneously into engagement through any clutch-operating device, such for example as that illustrated in re-issued Letters Patent No. 12,085 granted to me February 24, 1903. 100 For this purpose there is provided a collar n slidably mounted on the shaft f and adapted to be forced against the abutting face of the drum-carrying element g^4 by the clutch-operating screws n' threaded in a stationary 105 abutment formed by a part of the engine frame. The clutch-operating screws are moved to slide the collar along the shaft by means of levers n^2 (Figs. 1 and 2) connected by suitable linkage to the rocker shaft n^3 , the latter in turn being connected through links n^4 to the clutch-operating lever n^5 and under control of and near the operator. A second sliding collar (broken away in Fig. 3) 110 is also located at the opposite end of the shaft abutting against the face of the drum-carrying element h^6 and is adapted to be forced against the latter by means of clutch-operating screws and levers, the latter also connected to the rocker shaft n^3 in the same manner as has been already described. Movement of the clutch-operating lever causes simultaneous inward movement of the two sliding collars and also of the two 115 slidably mounted drum-carrying members, the latter having their inward peripheral faces in abutment against the faces of the rotatable members g^6 and h^4 , which are also 120 slidable on the shaft, so that the members g^6 and h^4 are caused to be moved inwardly and 125 130

with their cone surfaces in frictional engagement with the surfaces of the clutch member m . When this takes place in each case two of the three gearing elements are fixed relatively to the shaft and the third element carrying the winding drum is also locked directly to the driving shaft.

The full operation of the device will be apparent. The carriage is traversed from one point to another at the relatively high rate of speed by throwing the clutch-operating lever to drive the winding drums shown in Fig. 5 directly from the driving shaft. When properly positioned the carriage may be held with or without its load by holding the driving shaft against rotation, which may be done through the engine itself or by the brake bands g^7 and h^7 , if desired. When the load is ready for hoisting, the clutch lever may be thrown out of engagement and the friction lever into engagement to give the relatively slow reverse movement to the drums. When suitably elevated, the load is again traversed by throwing the clutch into and the friction out of engagement. The reversal of the hoisting or traversing movement may be effected by permitting reverse movement of the driving motor. In the present instance I have provided a suitable reversing gear indicated in outline in Fig. 2 (but partly removed from Fig. 1) and operated from the rock shaft o , the latter in turn being moved through links o' and the reversing lever o^2 . The slow speed which is utilized on the hoisting movement permits the application of increased power to the lifting of the load without, however, bringing any material strain upon the brake bands, since but a fractional part of the entire load is required to be held by each band. The members g^6 and h^6 which constitute the rotatable members of each planetary gearing system, are preferably provided with means which maintain them in generally the same relative position, such means herein being a series of pins m^2 which are secured to a radial flange m^3 upon the member h^4 and pass loosely through oppositely located holes in a corresponding flange upon the member g^6 . This permits each clutch face to adjust itself to its corresponding friction surface when the clutch is thrown into engagement, while still maintaining the two clutch members in a generally fixed relation. By securing the movable members together, the actual force necessary to apply to the clutch for holding the load while the carriage is being traversed, is reduced, for the planetary gearing connection between the shaft and the two members g^6 and h^6 being reversed the strains upon the two clutch faces are in opposite directions permitting the greater to be partly neutralized by the lesser.

Referring now to Figs. 6 to 9, inclusive, I have there shown an improved form of trol-

ley carriage which while adapted for general use in connection with hoisting and conveying systems is particularly adapted for employment in connection with some such system as has been described and is outlined in Figs. 4 and 5. The carriage is supported by the cable l (Figs. 4 and 5) upon the trolley wheels s , three in number and arranged in substantially the central plane of carriage to give the latter an even suspension. The hoisting winches k^4 , k^4 are located beneath the trolley wheels, symmetrically arranged with respect to the transverse central plane and coaxially secured to the hoisting drums k^1 , k^1 . The strands of the operating cables after being carried about the hoisting drums several turns pass to the opposite ends of the cable-way and return beneath the suspension sheaves s' located near the top of the carriage and at the opposite side of a central longitudinal plane from the hoisting drums k^4 , thereby to equalize the rope strain and maintain the even suspension of the carriage. The hoisting rope k^2 is wound and unwound at the same rate of speed from the two opposing drums, but in each case the line of draft will obviously move progressively lengthwise the periphery of the drums as successive convolutions of the rope are laid upon or unwound from the drum surface. In practice it has been found difficult to compel the rope to wind up evenly on the drum surface. Unless the suspension of the carriage is perfect, each successive convolution tends to climb upon the preceding one. If the rope is under strain and off the center of the carriage, the tipping effect upon the carriage is augmented and the climbing tendency of the rope further increased. In the present instance I have provided means for guiding the hoisting rope so that it is caused to be wound evenly upon its hoisting drum, and furthermore, have taken advantage of the two hoisting rope strands employed in the present case to neutralize the tipping effect upon the carriage of the one strand by that of the other. To this end the ropes are wound upon their respective drums starting from opposite sides of the central plane of the carriage, so that the line of draft of the two ropes approaches and recedes equally from the central plane of the carriage, or the center of gravity of the system, thus maintaining the resultant line of draft substantially fixed and causing no disturbance in the equilibrium of the carriage.

Referring to Figs. 7, 8 and 9, each hoisting rope k^2 is caused to pass through a guiding slot formed in a suitable guiding device s^2 carried each by a link s^3 connecting the corresponding free ends of equalizing bars s^4 , which are pivotally secured to the bottom of the trolley carriage frame; thus, as the ropes wind or unwind, the progressive movement of the one forces, through the reciprocal

action of the equalizing device, a correspondingly reverse movement of the other. This not only overcomes the tendency of the remaining rope to climb or double up, but also 5 neutralizes the strain thereof upon the suspension of the carriage, for whatever the position of one rope, the other must be equally distant from the central plane of the carriage. The guiding device s^2 is in the 10 general shape of an arc terminating in the head s^5 , which latter is adapted to bear upwardly against the cross connecting brace s^6 , so that in the upward movement of the hook, if the latter strike the guiding device at any 15 other than a central point, it will be deflected upwardly and rearwardly against the head s^5 , which latter is capable of withstanding the blow or strain.

It is to be understood that my invention 20 is not limited to the various details or form and arrangement of parts which have been herein described, the same being submitted for illustrative purposes, but that many modifications may be made in the system, as 25 I have herein described the same, without departing from the spirit of my invention.

Claim:

1. In a hoisting and conveying system the combination with a trolley carriage of pairs 30 of operating cable strands leading to said carriage from opposite directions, means for causing the strands of each pair to move in the same direction at one rate of speed for the traversing of the carriage and means also 35 causing the strands of each pair to move in opposite directions at a slower rate of speed for hoisting the load.

2. A hoisting and conveying system having a trolley carriage, pairs of operating cable 40 strands leading to said carriage from opposite directions and from a pair of winding drums, and means for rotating said drums at any one of a plurality of speeds.

3. A hoisting and conveying system having a trolley carriage, pairs of operating cable 45 strands leading to said carriage from opposite directions, and from a pair of winding drums, and means for rotating said drums at one speed or at a different speed and in a reverse 50 relative direction.

4. In a hoisting and conveying system the combination with a trolley carriage of pairs of operating cable strands leading to said carriage from opposite directions, a plurality 55 of winding drums controlling said strands, said drums being provided each with direct clutching means and speed reduction means between the drum and the source of driving power.

60 5. In a hoisting and conveying system the combination with a trolley carriage of pairs of operating cable strands leading to said carriage from opposite directions, winding drums controlling said strands, driving means

for said winding drums, clutching means between said drums and said driving means, speed reduction gearing and means for rendering effective said speed reduction gearing. 65

6. A hoisting and conveying system having a trolley carriage, pairs of operating cable 70 strands leading to said carriage from opposite directions, means for causing the strands of each pair to move in the same direction at one rate of speed, and means also for causing the strands of each pair to move in opposite directions at a different rate of speed. 75

7. In an apparatus of the class described, the combination with a trolley carriage of a plurality of winding drums thereon to and about each of which there leads a cable 80 strand, of means for maintaining the resultant line of draft of such cable strands substantially fixed with respect to a given point.

8. In an apparatus of the class described the combination with a trolley carriage of a 85 pair of winding drums thereon to and about each of which there leads a cable strand, of connected cable guiding means engaging each strand.

9. In an apparatus of the class described 90 the combination with a trolley carriage of rope winding drums thereon of cable guiding means comprising a pivoted equalizing bar, and means connected with said bar to engage the respective cables. 95

10. In an apparatus of the class described, the combination with a trolley carriage of winding drums thereon of rope guiding means comprising a plurality of pivoted equalizing bars, links connecting said bars and rope 100 guiding devices carried by said links.

11. In an apparatus of the class described a trolley carriage, a pair of drums to and about each of which there leads a cable strand and means to maintain the lines of 105 draft of the respective cables substantially symmetrical with respect to the center of gravity of the carriage.

12. The combination with a trolley carriage of a pair of winding drums thereon with 110 cable strands leading thereto, of reciprocally acting guiding means for said strand.

13. The combination with a trolley carriage of a rope winding drum thereon of means for progressively laying the successive 115 convolutions of said rope lengthwise the periphery of said drum.

14. The combination with a trolley carriage of a plurality of rope winding drums thereon and rope equalizing means therefor. 120

15. In an apparatus of the class described, a cable-way, a trolley carriage sustained thereon, a pair of rope-winding drums lying transversely said carriage, cable strands depending from said drums and adapted to be 125 wound on or unwound from the same, a rope-guiding device for each of said depending strands, and an equalizing bar connected

to each of said rope-guiding devices and
adapted to cause reciprocal movement of the
same thereby to maintain the lines of draft
of the respective strands substantially sym-
metrical with respect to the center of gravity
of the carriage.

In testimony whereof, I have signed my

name to this specification, in the presence of
two subscribing witnesses.

ALMON E. NORRIS.
